Martin de Botelho, New York, N. Y.

Application November 20, 1945, Serial No. 123,920

Term of patent 14 years

(Cl. D86—10)

To all whom it may concern:

Be it known that I, Martin de Botelho, a citizen of Brazil and residing at New York, in the county of New York and State of New York, have invented a new, original, and ornamental Design for a Lipstick Case or the like, of which the following is a specification, reference being had to the accompanying drawing, forming part thereof, and in which

Fig. 1 is a perspective view of a lipstick case

or the like embodying my new design in closed position;

Fig. 2 is a perspective view thereof in open position; and

Fig. 3 is a top plan view thereof.

I claim:

The design for a lipstick case or the like, substantially as shown.

MARTIN DE BOTELHO.
